Primary Examiner — Leanne Was-Englehart(74) *Attorney, Agent, or Firm* — Browdy and Neimark, PLLC(57) **CLAIM**

The ornamental design for a low-profile threshold of a safety gate, as shown and described.

DESCRIPTION

FIG. 1 is a perspective view of a low-profile threshold of a safety gate showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged left side elevation view thereof;

FIG. 9 is an enlarged right side elevation view thereof; and,

FIG. 10 is an operational perspective view thereof.

The broken lines shown are included for the purpose of illustrating environment and unclaimed portions of the article and form no part of the claimed design.
